(No Model.)

A. W. FORCE.
HORSE HAY RAKE.

No. 269,038.

Patented Dec. 12, 1882.

Inventor:
Albert W. Force
for J. C. Tastorwally

UNITED STATES PATENT OFFICE.

ALBERT W. FORCE, OF ITHACA, NEW YORK, ASSIGNOR TO THE ITHACA MANUFACTURING WORKS, OF SAME PLACE.

HORSE HAY-RAKE.

SPECIFICATION forming part of Letters Patent No. 269,038, dated December 12, 1882.

Application filed September 28, 1882. (No model.)

To all whom it may concern:

Be it known that I, ALBERT W. FORCE, a citizen of the United States, residing at Ithaca, in the county of Tompkins and State of New York, have invented certain new and useful Improvements in Horse Hay-Rakes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to dumping attachments for horse hay-rakes; and it consists of an improved arrangement of devices for releasing the dump, as hereinafter more fully described and claimed.

20 In the annexed drawings, illustrating the invention, Figure 1 is a side elevation of a portion of the horse hay-rake provided with my improved dumping attachments, the rake-teeth being shown in position for raking. Fig. 2 is a plan, some parts being broken off. Fig. 3 is a side elevation, the wheels being removed, showing the teeth in position for dumping. Figs. 4, 5, and 6 are details hereinafter referred to.

25 30 Like letters of reference are used to designate the same parts in the several views.

Referring to said drawings, the dotted lines designated by the letter A represent one of the driving-wheels, provided with the usual inner rim, a, also shown in dotted lines.

35 B denotes one of the cross-bars of the main frame.

C is the rake-head, which in this instance is also the axle, and D is the rider-bar.

40 Pivoted to a lug or bearing, b, secured to the cross-bar B, is a hand-lever, E, composed of the straight portion or handle c and an irregularly elliptical body, d, said parts c and d being firmly riveted or otherwise securely connected. The rear or elliptical end, d, of the lever E is pivotally secured between the forward ends of the connecting bars or rods F F, the rear ends of which are pivoted to a triangular plate or connection, G, which is rigidly secured to and between the rake-head C and

rider-bar D, said parts C D and connecting-plate G being adapted to turn together in raising or lowering the rake-teeth e e, which are secured to the bar or head C in any suitable manner.

55 Securely fastened to the rider-bar D, by means of staples f, is a rock-shaft, H, formed in one or two parts, and provided with the usual fork-irons for gripping the rim a during the operation of dumping, and having a cranked portion, h, which is connected, by a chain, g, or other flexible connection, with the rear end of a rod, i, the forward end of which is connected to the forward downwardly-curved end of a foot-lever, I, which is pivoted in bearings k k on the cross-bar B. This foot-lever I is connected to the lever E and connecting-bars F F by means of a curved releaser-bar, K, which holds the bars F F, plate G, and rider-bar D in such position that the fork-irons on the ends of the rock-shaft H will be released from the rim a, so as not to grip the same except when the devices are operated for the purpose of dumping the rake.

60 70 75 The releaser K in the end pivoted to the foot-step I has a slot, m, Fig. 6, through which the connecting-pin is passed, greater freedom of action being thus allowed to the releaser, so that while the rake is being raised for dumping, by pressure on the foot step or lever I, 80 the releaser at a certain point in the upward movement releases the fork-irons from their grip on the rims.

85 On the rear of the lever E, Fig. 5, is a lug or projection, o, which, by impinging on a rubber spring, p, Figs. 4 and 5, attached to a plate on the cross-bar B, diminishes jar when the lever is thrown forward in lowering the rake-teeth. The draft-animals as well as the rake are thus relieved from undue strain and jar in dumping.

90 A spring, s, is connected with the rider-bar D and rock-shaft H between the ends of the crank, as shown in Figs. 1, 2, and 3, and by pressing said crank backward assists in holding the parts in position for the wheels to revolve freely.

95 By exerting pressure with the foot upon the lever I to dump the load the attachment K will be caused to act to keep the rake-teeth 100

raised without dragging the wheels, the teeth being allowed to fall at pleasure by simply removing pressure from the foot-lever.

Having thus described my invention, what I claim as new, and desire to secure by Letters Patent, is—

1. In a horse hay-rake, the combination, with the levers E I, rake-head C, rider-bar D, and connecting means F G, of the releaser-bar K, attached at one end to the foot-lever I, and at its opposite end to the hand-lever E and connections F, substantially as and for the purpose described.

2. In a horse hay-rake, the combination of the wheels A, having rims *a*, the frame B, rake-head C, rider-bar D, plate G, connecting the rake-head and rider-bar, the levers E I, connecting-bars F F, releaser-bar K, cranked rock-shaft H, having forked ends adapted to engage with the rims *a*, and the chain *g* and rod *i*, connecting said shaft to the foot-lever, all substantially as and for the purpose described.

3. In a horse hay-rake, the combination, with

the foot-lever I, of the curved releaser-bar K, loosely pivoted at one end to said foot-lever, 25 and connected at its opposite end to the hand-lever E, and connecting bars or rods F F, substantially as described.

4. In a horse hay-rake, the combination of the cross-bar B, having spring *p*, the levers I 30 and E, pivoted in suitable bearings on said bar, the lever E being provided with lug *o*, the rake-head C, rider-bar D, connecting means F G, curved releaser-bar K, connected with the hand and foot levers, the cranked rock-shaft H, having irons adapted to grasp the rims on the driving-wheels, and the connections *i g* and spring *s*, all substantially as and for the purpose described.

In testimony whereof I affix my signature in 40 presence of two witnesses.

ALBERT W. FORCE.
